United States Patent Office.

WILLIAM W. BINNY, OF AUBURN, NEW YORK, ASSIGNOR TO S. N. BIERCE,
OF NEW YORK CITY.

Letters Patent No. 104,253, dated June 14, 1870.

IMPROVEMENT IN GAS-MACHINES.

The Schedule referred to in these Letters Patent and making part of the same.

I, WILLIAM W. BINNY, of the city of Auburn, in Cayuga county, and State of New York, have invented a certain Improvement in Gasoline Gas-blowing Machine, of which the following is a specification.

Nature and Objects of the Invention.

My invention relates to the outlet end of the blowing-cylinder, and consists in making the opening in that end further from the radial line of the float or bucket than it is at the inlet end of the same, for the purpose of producing a more even pressure on the gasoline vapor as it approaches the burner.

Description of the Drawing.

Figure 1 is a stretchout of the blowing-cylinder.

Figure 2 is a vertical longitudinal section, taken through the center, showing all the parts in the collective relation.

Figure 3 is a cross vertical section of the blowing-cylinder, taken through the center.

Figure 4 is an elevation of one of the blowing-cylinders, showing the end; the points of the darts showing the place where the gasoline vapor enters the same.

Figure 5 is a side view of the blowing-cylinder, with the cover removed, for the purpose of showing the position of the float J to the inlet-opening U, and to the outlet-opening V, as my invention consists of making the distance from the said outlet-opening to the float J more, by some twelve to fifteen degrees, than the distance from the float J to the inlet opening U, measured around the diameter.

A is the inlet-pipe, connecting with and opening into the carbureter, not shown, from which the gas is drawn, and it moves up the said pipe, as shown by the dart in the lower end, from which it passes into the chamber B.

The head C of the blowing-cylinder D is made gas-tight, except the hole in the center, through which the pipe A enters the end of the said cylinder.

The head E is open, like the head F; both are alike, and shown in fig. 4, where the points of the darts show where the gas enters the cylinder through said head, and if these darts were reversed they would show where the gas escapes through the head F.

The floats G H I J K have the edges nearest the shaft L straight, and parallel therewith.

The opposite edge of the said floats are made in a spiral form, as shown at M M, &c., the ends at M M, &c., terminating at and forming a part of the heads E and F.

The external case N is filled with water up to the line O, and covers three-fifths ($\frac{3}{5}$) of the external case and the blowing-cylinder, as shown at fig. 3. The blowing-cylinder may be caused to rotate slowly by any force applied thereto.

Operation.

Let us suppose the cylinder to be turning in the direction of the dart P. When the opening at the point of the dart Q rises above the water-line O, the chamber R will gradually fill with gas, by drawing it through the pipe A, in the same order that water recedes from the said chambers by the rotation of the cylinder, and, when the opening at the point of the dart Q passes below the water-line on the opposite side, at 1, the other end of the chamber R is opened by passing above the water-line, and the gas is thus passed through the chamber R into the cylinder N, at S, and from thence up the outlet-pipe T to the burners.

Each chamber has a spiral space formed by the floats, which extends around two-fifths ($\frac{2}{5}$) of the diameter of the blowing-cylinder; consequently no gas can pass through the cylinder from the chamber B, except as fast as the water recedes from the inlet end, caused by the rotation of the cylinder.

This arrangement gives a very steady and uniform supply of gas to the burner, and on that account produces a steady and constant light.

I claim as my invention—
Extending the outlet-opening V about twelve to fifteen degrees further around the shaft, from the float J, than the inlet-opening, substantially as above described.

WILLIAM W. BINNY.
